CLAIM

The ornamental design for a safety closure device, as shown and described.

DESCRIPTION

FIG. 1 is a diagrammatic perspective view of the safety closure device, in the closed position, in full lines with a cabinet and handles shown in broken lines representing environmental association matter being for illustrative purposes only and forming no part of the claimed invention.

FIG. 2 is a diagrammatic perspective view of the safety closure device in the open position.

FIG. 3 is a front elevational view thereof.

FIG. 4 is a rear elevational view thereof.

FIG. 5 is a top plan view thereof, the bottom plan view being a mirror image of the top plan view.

FIG. 6 is a left side elevational view of the safety closure device; and,

FIG. 7 is a right side elevational view thereof.
